The ornamental design for a packaging blank, as shown and described.

DESCRIPTION

FIG. 1 is a top plan view of a packaging blank showing our new design;

FIG. 2 is a side elevation view thereof; and,
FIG. 3 is a front elevation view thereof.

The dotted lines shown in FIG. 1 represent perforations and form no part of the claimed design.

The stippled areas represent areas that contrast to the adjacent non-stippled areas.

The vertical and horizontal shade lines are used to show that the surface is substantially flat and not to be interpreted as surface ornamentation.
